(57) **CLAIM**

The ornamental design for a massage head boot, as shown and described.

DESCRIPTION

FIG. 1 is a top plan view of the massage head boot;
 FIG. 2 is a bottom perspective view thereof;
 FIG. 3 is an alternate bottom perspective view thereof;
 FIG. 4 is a bottom plan view thereof; and,
 FIG. 5 is a side elevation view thereof, the opposite side
 being a mirror image thereof.
 The broken lines shown in FIGS. 1-5 are for illustrating
 environmental structure and form no part of the claimed
 design.
